UNITED STATES PATENT OFFICE.

THOMAS O. SCHRADER, OF ALLENTOWN, PENNSYLVANIA, ASSIGNOR TO THE DENT HARDWARE COMPANY, OF FULLERTON, PENNSYLVANIA, A CORPORATION OF PENNSYLVANIA.

TOY CAP-PISTOL.

1,141,904.

Specification of Letters Patent.

Patented June 1, 1915.

Application filed January 28, 1915. Serial No. 4,810.

To all whom it may concern:

Be it known that I, THOMAS O. SCHRADER, a citizen of the United States, residing at Allentown, in the county of Lehigh and 5 State of Pennsylvania, have invented certain new and useful Improvements in Toy Cap-Pistols, of which the following is a specification.

My invention relates to a toy cap-pistol; 10 and in such connection it relates to the particular shape and arrangement of the hammer in conjunction with the particular type of slideable trigger operating in range of a leaf spring positioned in connection with the 15 hammer and a corner of the hand-hold of the pistol and in the path of the trigger, when operated to uncock said hammer to fire the cap, the said trigger having rear arms of different lengths, one whereof engages the 20 said spring in one position of the said hammer to readily uncock the same by a slight manual pressure exerted and the said trigger limited in the extent of its movement in one direction by one portion thereof engaging an 25 offset of the barrel or stock of the pistol.

The nature and characteristic features of 30 my present invention will be more fully understood from the following description taken in connection with the accompanying drawings forming part hereof, in which—

Figure 1, is a longitudinal central sectional view through the toy cap-pistol, embodying the essential features of my said invention, showing the hammer cocked and 35 the bowed position of the leaf spring in such condition of the toy-pistol. Fig. 2, is a side elevational view of the pistol and the uncocked position of the hammer, and in dotted outline the condition of the leaf-spring in 40 such position thereof; and Figs. 3 and 4, are respectively end views of the said pistol.

Referring to the drawings α , is the barrel or stock of the pistol of a kind that has become known as the scout-type, with a rear 45 depending hand-hold α^1 . With reference to Fig. 1, α^2 , is the hammer, the head α^3 , of which is adapted to strike the end face α^4 , of the barrel or stock α , as shown in Fig. 1, for discharging the paper or other cap against 50 the same to be fired by the said hammer. The hammer α^2 , has a perforated body α^5 ,

and is fitted to a pin b , and it is also provided with a notched extremity α^6 , to engage one end of a leaf-spring c , and extending slantingly therefrom to a stop d , formed by 55 the left hand corner of the hand-hold α^1 . The trigger e , is arranged to slide in a way e^1 , provided in the hand-hold α^1 , therefor, as clearly shown in Fig. 1. This trigger has two arms e^2 and e^3 , of different lengths, one 60 being adapted to readily engage the leaf-spring c , above a central point thereof, in the bowed condition of said spring c , and the cocked position of the hammer α^2 , for discharging a cap against the face α^4 , of the 65 pistol barrel or stock to be struck by the said hammer, when the slideable trigger e , is manually pressed inward and against the bowed spring c , to cause it to assume a slanting inclined position such as shown in dotted outline in Fig. 2, to that it occupies with the hammer in a cocked position, as shown in Fig. 1. The extent or range of forward movement of the trigger e , is limited by one 70 corner thereof engaging an offset portion α^7 , of the stock or barrel α , as clearly shown in Figs. 1 and 2.

Having thus described the nature and object of my invention, what I claim as new and desire to secure by Letters Patent is:— 80

A toy cap-pistol having a barrel provided with a depending hand-hold, a hammer having a perforated body and notched extremity, said hammer mounted on a pin in said hand-hold, a leaf spring engaging the notched extremity of said hammer and a slideable trigger having two rear arms of different lengths, 85 said trigger movable crosswise in said hand-hold and one of said arms arranged to engage said spring with the hammer in a cocked position and said trigger extending through one end of the casing of said hand-hold and engaged at one corner by the offset in the barrel of said pistol, substantially as and for the purposes described. 90

In witness whereof, I have hereunto set my signature in the presence of the two subscribing witnesses.

THOMAS O. SCHRADER.
